FROST AND MOISTURE ABSORBER FOR WINDOWS

Original Filed July 25, 1929

FIG-1

FIG-2

FIG-4

FIG-3

Carl A. Randolph,
INVENTOR.
BY Walter N. Haskell,
his ATTORNEY

UNITED STATES PATENT OFFICE

CARL A. RANDOLPH, OF ROCK ISLAND, ILLINOIS

FROST AND MOISTURE ABSORBER FOR WINDOWS

Application filed July 25, 1929, Serial No. 380,903. Renewed October 5, 1931.

My invention has reference to a frost and moisture absorber for windows, and aims to provide a convenient and reliable means for preventing the collection of water on the window sill, and injury to the walls below such sill. It is of special use in the colder months, when the frost forms on the insides of the windows, and, upon melting, runs downwardly upon the sill and wall.

10 One of the purposes of the invention is to provide a receptacle at the lower part of the window sash, containing a quantity of absorbent material, which will receive and retain the moisture until it is removed therefrom. 15 The receptacle is so constructed and arranged as to permit of the ready removal of the absorbent material for emptying, and replacement thereof.

20 Another object of the invention is to provide means for holding the same rigidly in position against the lower rail of a sash, and so that it can be quickly detached therefrom. 25 Another purpose thereof is to provide a base-strip for securing in rigid position on a window-sill and a moisture absorbing portion which is movable with relation to the base, so that it can be turned or otherwise moved out of the way when it is desired to remove or replace the base, or perform any act 30 in connection therewith.

The above-named, and other features and advantages of the invention will more fully appear from the following specification, reference being had to the accompanying drawings, in which:

35 Fig. 1 is an outer face view of the invention, as it appears when in use.

40 Fig. 2 is an end view thereof, with the parts closed.

45 Fig. 3 is a cross-section on the broken line 3—3 of Fig. 1, with the cap-plate 17 raised.

Fig. 4 is a cross-section on the broken line 4—4 of Fig. 1.

50 The invention is intended to be of sufficient length to fit a window of established size, and to extend from one side of the sash to the other. Changes can be made in the length and other dimensions thereof to make the same adaptable to windows of different sizes.

The reference number 1 indicates the lower

55 rail of a window sash, and 2 the sill on the inner side thereof. Said rail is provided with a handle 3, and projected upwardly from the rail is a pane of glass 4. The invention comprises a strip 5, forming the base of the device, beveled at its lower inner edge to prevent binding on the rail, and provided with a pair of thin plates 7, which are forced downwardly between the sill and sash, and by means of which the base is held in place.

60 A horizontally disposed strip 9 is secured to the base 5 by means of hinges 10, the inner part of said strip being channeled to form a trough, of which the glass 4 comprises the outer side. The outer edge of the strip 9 has attached thereto a strip of rubber 11, which bears against the glass when the device is in use, and takes care of any water that leaks through from above. In the channeled portion of the strip 9 is a lining 14 of flexible rubber, looped at the ends 15. When in position the outer edge of the lining 14 is pushed upwardly by the glass 4, forming a receptacle, or container for a strip of artificial sponge or other absorbent material at 16. 70 For convenience in manufacture the sponge is formed in two or more sections.

75 The strip 9 is held in rigid relation with the base 5 by means of a pair of hooks 12, pivoted to the ends of the base, and engaging screws 13 in the ends of the strip 9.

80 A cap-plate 17 is secured to the inner edge of the strip 9 by hinges 18, permitting such cap-plate to be raised separately, as shown in Fig. 3. The plate 17 when in lowered position covers the greater part of the strip 16, with the exception of a space adjacent to the window to permit downward movement of the moisture. Said cap-plate is held normally in such lowered position by means of 85 hooks 19 pivoted to the ends of the strip 9, and engaging screws 20 in the ends of the plate 17.

90 When the device is in operation the moisture which runs down the inner face of the glass 4 is directed into the absorbent material 16, in which it is held, and at such intervals as may be necessary the cap-plate 17 is released and tipped out of the way, permitting the absorbent material to be removed 100

and squeezed into a larger receptacle for throwing out. The sponges are then replaced and the plate 17 fastened down again. By loosening the hooks 12 the upper part of the apparatus can be turned away from the glass 5 for any purpose, as shown in Fig. 2.

The amount of moisture to come from the frost on a window is not very considerable, and the size of the receptacle therefor in the 10 present device is ample to take care of the same for several hours. During the night the amount of evaporation is not likely to be so great as in the day-time.

To detach the base 5 from the window-sill 15 the base and sash are raised together until the plates 7 clear the sash. The strips 5, 9, and 17 are shown formed of wood, but other material may be employed therefor.

What I claim, and desire to secure by Letters Patent, is:

20 1. A device of the class described, comprising a base, adapted for rigid support on the sill of a window, a trough member supported on said base, and absorbent material 25 contained in said trough member.

2. A device of the class described, comprising a base, adapted for rigid support on the sill of a window, a trough member supported on said base and adjacent to the glass of the 30 window, absorbent material in said trough member, and a cap-plate hingedly connected with said trough member, and holding said absorbent material in place.

3. A device of the class described, comprising a base, provided with fastenings insertable between the sill of a window and the frame thereof, a channeled strip hinged to said base, the channel forming a trough in conjunction with the glass of a window, a 40 rubber lining in said channel, strips of absorbent material in said trough, means for holding said strip and base in fixed relation, a cap-plate hinged to said strip, holding said absorbent material in place, and means for holding said cap-plate in fixed relation with 45 said strip.

4. A device of the class described, comprising a base member adapted for support on the sill of a window, a channeled strip supported on said base, adapted to bear against 50 the face of the window at its outer edge, and forming with the glass of the window a container, a flexible rubber lining for said container, adapted to direct moisture into the 55 same from the glass, and absorbent material held removably in said container.

In testimony whereof I affix my signature.
CARL A. RANDOLPH.
